The ornamental design for an upper section of an excavator bucket, as shown and described.

(51) **LOC (13) Cl.** **15-03**

DESCRIPTION

(52) **U.S. Cl.**

The present application is also related to U.S. Design application Ser. No. 29/719,364, U.S. Design application Ser. No. 29/719,367, and U.S. Design application Ser. No. 29/719,366, all of which are concurrently filed herewith, and the disclosures all of which are incorporated herein by reference.

USPC **D15/32**

FIG. 1 is an upper perspective rear view of an upper section of an excavator bucket according to our design;

(58) **Field of Classification Search**

FIG. 2 is a lower perspective front view thereof;

USPC D15/28, 29, 32
CPC E02F 3/40; E02F 3/96; E02F 3/04; E02F 3/962; E02F 3/404; E02F 3/401; E02F 9/24; E02F 9/28; B65G 2812/02742; B65G 17/36

FIG. 3 is a front view thereof;

FIG. 4 is a top plan view thereof;

FIG. 5 is a rear view thereof; and,

FIG. 6 is a right side view thereof, the left side view being a mirror image thereof.

See application file for complete search history.

The broken lines shown in the drawings are for the purpose of illustrating environmental structure that forms no part of the claimed design.
